UNITED STATES PATENT OFFICE

HERBERT C. OTIS, OF SHREVEPORT, LOUISIANA

BOTTOM HOLE CHOKE

Application filed December 27, 1932. Serial No. 649,066.

This invention relates to a bottom hole choke for use in oil wells, and more particularly to a device for use in producing flow in oil wells in which the quantity of gas normally produced with the oil is insufficient to maintain a continuous flow of oil from the well at the desired rate of oil production, even though the most efficient possible use of the gas is accomplished by means of bottom hole chokes.

It often happens in such wells that a considerable amount of gas, called casing-head gas, is stored under pressure in the space between the casing and tubing above the well fluid level. If the fluid level is some distance above the tubing inlet, it is probable that unless some special means are provided, use cannot be made of the casing-head gas to assist in raising the oil through the tubing. since the accumulation of oil around the lower portion of the tubing acts as a fluid seal preventing the gas from entering the base of the tubing. To permit use of this casing-head gas, small perforations called jets are sometimes made at intervals in the tubing string, these perforations admitting a portion of the gas into the tubing string to assist in flowing the oil. When it is desired to bring this gas into the tubing string at a point beneath the fluid level, use has been made of an additional partial string of small diameter tubing which is clamped to the larger string of tubing and extends from its point of entry into the larger tubing to a point above the fluid level of the well, thus permitting the casing head gas, if under sufficient pressure, to pass to the interior of the larger tubing.

Neither of these methods permits of ready adjustment of the control rate of entry into the tubing of relative amounts of oil and gas. It is necessary, in order to increase or decrease the area of the openings through which the fluid or gas enters the tubing, to pull and re-run the tubing.

An important object of this invention is the provision of an apparatus for use under such circumstances which will permit the ready change of the diameter of either the gas inlet port or of the oil inlet port.

A further, and more specific object of the invention is the provision of a readily pullable choke which is so constructed that it carries removable and interchangeable orificed beans controlling the rate of flow of both the gas and oil.

A further object of the invention is the provision of a construction such that entry of oil may be terminated at any time while the supply of gas is continued, with the result that the tubing may be virtually emptied of fluid following any flowing operation.

These and other objects I attain by the construction shown in the accompanying drawings wherein, for the purpose of illustration, I have shown a preferred embodiment of my invention and wherein:

Fig. 1 is a vertical sectional view showing apparatus constructed in accordance with my invention installed in a well;

Fig. 2 is an enlarged detail sectional view through the nipple and choke constructed in accordance with my invention;

Fig. 3 is an elevation of the tool employed when unseating the valve;

Fig. 4 is a section on line 4-4 of Fig. 2;

Fig. 5 is a section on line 5-5 of Fig. 2;

Fig. 6 is a section on line 6-6 of Fig. 2;

Fig. 7 is a vertical sectional view showing the blade section of the choke in elevation; and

Fig. 8 is a fragmentary sectional view through a slightly modified form of choke.

Referring now more particularly to the drawings, the numeral 10 generally designates the casing of a well, and 11 the tubing thereof having an outlet valve 12 at its upper end.

In accordance with my invention, the tubing is provided at a suitable point adjacent its lower end with a locating device in the form of a specially constructed nipple 13 having intermediate its ends a port 14 communicating with an integral L fitting 15 adapted to receive the lower end of a gas admission tube 16 equipped with a downwardly-opening check valve 16-a. This gas admission tube, as shown in Fig. 1, may extend above the normal fluid level in the well which is indicated at 17. The bore of

- the nipple has upper and lower sections B and B' which are of slightly different diameter, the upper section B being the larger, and intermediate these sections has a section of still more increased diameter indicated at 5 18. The increase in diameter at 18 forms upwardly and downwardly facing shoulders 19 and 20. The downwardly facing shoulder is abrupt, and preferably somewhat undercut, while the upwardly facing shoulder 19 should be slightly beveled so that packing elements may be run thereby without damage, this being necessary, as will hereinafter become obvious.
- 15 Within this nipple I employ a choke 21 which is formed in upper and lower sections 22 and 23, each having an axial bore therethrough. Near the lower end of the upper section 22 this section is externally reduced 20 to provide an annular recess 24 housing a plurality of locking blades 25. The lower ends of the locking blades are normally confined by a sleeve 26 secured to the lower end of the section 22 and projecting slightly 25 above the lower end of the annular chamber 24. Sleeve 26 is secured by means of frangible elements 27, and blades 25 have springs 28 co-acting therewith at a point slightly above the upper end of the sleeve so that the 30 upper ends of the blades are urged outwardly. The blades are held against vertical or circumferential movement by means of locking lugs 29 and each blade has upon its outer face an upwardly facing shoulder 35 30 adapted to engage beneath sleeve 26 under circumstances presently to be described. Above the blades, section 22 is equipped with upwardly and downwardly-facing packings 31 and 32.
- 40 The lower section 23 is, at its upper end, made of slightly less diameter than the interior diameter of the nipple and is equipped with a port connecting its interior and exterior, which port comprises an orifice 33 45 formed in a removable plug 34, removal and replacement of which will provide for a change of orifice size. At its lower end, the bore of section 23 is closed by an orificed bean 35, the lower end of the orifice of this 50 bean being formed as a valve seat for co-action with a valve 36 having a stem 37 extending upwardly through the orifice of the bean and projecting above the upper end of the bean. Valve 36 is spring-seated and 55 guided within an extension 38 of the bean, which extension is pierced at 39 for the flow of fluid.
- 60 When the choke is lowered into place in the tubing, the springs 28 will force the 65 blades 25 outwardly so that they will catch beneath the shoulders 20 and prevent upward displacement of the choke. Downward movement of the choke is prevented by 65 position of sleeve 26 to the shoulder 19.
- the orifice 33 will be placed in communication with the gas inlet port 14, the downwardly-facing packer 32 of the upper section and the upwardly facing packer 40 of the lower section sealing against escape of 70 gas pressure except through this orifice. The valve 36 is unseated by inserting through the bore of the choke a valve-operating stem 41, which is preferably attached to the lower end of a weight 42 having guides 43 for guiding 75 co-action with the walls of the tubing. The actuating stem 41 engages the upper end of stem 37 to unseat the valve and actuating stem 41 is preferably made of such length that the weight comes to rest on top of the 80 choke and is supported thereby when the valve is opened to the desired extent. Ports 44 in the lower end of the weight will conduct fluid from the bore of the choke to the exterior of the weight. Weight 42 is supported from a small line leading to the well head. It will be obvious that employing apparatus of this character it is possible to cut off the flow of oil at any time at the bottom 85 of the well without cutting off the intake of gas through orifice 33, with the result that incoming gas may continue to discharge the oil from the tubing until substantially all oil above the level of the orifice has been ejected. Under these circumstances, there will be no 90 difficulty in instituting the flowing operation, difficulty in starting being ordinarily due to the pressure resistance of tubing contained fluid.
- 95 Apparatus of this character is particularly 100 desirable in well operation under the present control system wherein the output of each well is limited to a given number of barrels per day. With the ordinary apparatus, it is difficult, if not impossible, to determine 105 when the tubing contains the desired amount of oil and, accordingly, the only measure of output is the actual discharge at the upper end of the casing. With a choke of this 110 character employed in combination with the gas pressure lift, knowing the well pressures, it is possible to compute with great accuracy the time through which the well must operate to provide an ultimate delivery of the required barrelage. If it is found that the size 115 of one or both fluid inlets must be changed, a combined pulling tool and jar, preferably of the type shown in my prior application, filed November 24, 1931, Serial No. 577,087, for Safety pulling tool for well equipment, is 120 lowered into the well and engaged with the upper end of the choke which is adapted at 125 44 for such engagement. By jarring downwardly upon the choke, the frangible pins 27 are broken permitting sleeve 26 to move 130 upwardly with respect to the choke. When the lower end of sleeve 26 is above the shoulders 30 of the blades, the upper ends of the blades are forced inwardly so that they will pass the shoulder 20, the springs 28 being at 135

260
this time below the lower end of the sleeve so that they serve to urge the lower ends of the blades outwardly. The choke is withdrawn, suitable changes made in the inlets, and sleeve 26 restored to its proper position, after which the assemblage can be re-run in the well.

12 The structure shown in Fig. 8, is identical with that previously described with the exception of the fact that the bean 35 and associated parts, as shown in Figs. 1 to 7, is substituted for by a downwardly movable bean 45 normally held in engagement with a valve seat 46 formed on the lower end of the choke 15 by a light spring 47, the weight of which is just sufficient to hold the bean against its seat.

23 While a structure of this character does not incorporate the advantage of ability to terminate flow of oil at a desired point, it incorporates in the choke structure those advantages obtained by the use of downwardly releasing bean as set forth in my copending application, Serial No. 627,479, filed August 4, 1932, for Removable choke.

23 While I have above consistently referred to the gas in the well, it will be understood that in many wells the gas pressure provided is not sufficient for causing flow and under these circumstances it is the common practice to 23 inject in the upper end of the casing air under pressure for this purpose. Therefore, in consideration of the appended claims, the term "gas" will be understood as including any fluid under natural or artificial pressure 35 which may be employed in the manner described.

23 Since the structure hereinbefore set forth is capable of considerable modification without in any manner departing from the spirit of my invention, I do not wish to be understood as limiting myself thereto except as herein-after claimed.

I claim:

45 1. In oil well apparatus of the type described, the combination of a tubing having gas and oil inlets in the lower portion thereof simultaneously admitting oil and gas to the tubing, and means for closing the oil inlet while leaving the gas inlet open.

50 2. In oil well apparatus of the type described, the combination of a tubing having gas and oil inlets in the lower portion thereof simultaneously admitting oil and gas to the tubing, orifices controlling said gas and oil inlets, and means for closing the orifice controlling the oil inlet while leaving the orifice controlling the gas inlet open.

55 3. In oil well apparatus of the type described, the combination of a tubing having gas and oil inlets in the lower portion thereof simultaneously admitting oil and gas to the tubing, orifices controlling said gas and oil inlets, means for closing the orifice controlling the oil inlet while leaving the orifice 60 controlling the gas inlet open, and a mem-

ber removable through the tubing and mounting said orifices.

4. In oil well apparatus of the type described, the combination of a tubing having a gas inlet at a point below the normal level of oil in the well, an oil inlet orifice in said tubing adjacent said gas inlet, said gas inlet and oil inlet orifice simultaneously admitting oil and gas to the tubing and means to close the oil inlet orifice while leaving the gas inlet open.

5. In oil well apparatus of the type described, the combination of a tubing having a gas inlet at a point below the normal level of oil in the well, an oil inlet orifice in said tubing adjacent said gas inlet, said gas inlet and oil inlet orifice simultaneously admitting oil and gas to the tubing means to close the oil inlet orifice while leaving the gas inlet open, and a member removable through the tubing and mounting said orifice.

6. The method of operating oil wells comprising simultaneously admitting oil and gas to the lower end of the tubing while metering the oil, cutting off the admission of oil after a predetermined amount thereof has been admitted to the tubing, continuing the admission of gas until the oil is discharged from the tubing, resting the well while still preventing the admission of oil to the tubing and then resuming operation of the well by reducing the gas pressure in the tubing and resuming the admission of oil to the tubing.

7. The method of operating oil wells comprising simultaneously admitting oil and gas to the lower end of the tubing while metering the oil and gas admitted to the tubing, cutting off the admission of oil after a predetermined amount thereof has been admitted to the tubing, continuing the admission of gas until the oil is discharged from the tubing, resting the well while still preventing the admission of oil to the tubing and then resuming operation of the well by reducing the gas pressure in the tubing and resuming the admission of oil to the tubing.

8. The combination in an oil well of a tubing having a gas inlet and an oil inlet, a bored member removably mounted in the tubing having a gas inlet orifice and an oil inlet orifice communicating with the gas and oil inlets of the tubing respectively, and sealing means on the member preventing passage of fluids exteriorly of the member from one to the other of said orifices.

9. The combination in an oil well of a tubing having a gas inlet and an oil inlet, a bored member removably mounted in the tubing having a gas inlet orifice and an oil inlet orifice communicating with the gas and oil inlets of the tubing respectively, and sealing means on the member preventing passage of fluids exteriorly of the member from one to the other of said orifices or from either orifice to the tubing above the member.

10. The combination in an oil well of a tubing having a gas inlet and an oil inlet, a bored member removably mounted in the tubing having a gas inlet orifice and an oil inlet orifice communicating with the gas and oil inlets of the tubing respectively, sealing means on the member preventing passage of fluids exteriorly of the member from one to the other of said orifices, and means to seal 5 the oil inlet orifice while leaving the gas inlet orifice open.

11. The combination in an oil well of a tubing having a gas inlet and an oil inlet, a bored member removably mounted in the tubing having a gas inlet orifice and an oil inlet orifice communicating with the gas and oil inlets of the tubing respectively, sealing means on the member preventing passage of fluids exteriorly of the member from one to 15 the other of said orifices or from either orifice to the tubing above the member, and means to seal the oil inlet orifice while leaving the gas inlet orifice open.

12. In an oil well apparatus of the type described, and in combination, a tubing nipple having an area of increased diameter affording upwardly and downwardly-facing shoulders, a choke insertable in said tubing including a plurality of locking blades, springs 25 acting upon the locking blades intermediate the ends thereof to urge them outwardly, a collar embracing the lower ends of the blades to prevent expansion thereof whereby said springs act to urge the upper ends of 30 the blades outwardly to cause said blades to engage beneath the downwardly facing shoulder of the nipple when the choke is inserted therein, and means maintaining the collar in position upon the choke, said means 35 being displaceable upon the application of downward pressure to the choke with the collar in engagement with the upwardly-facing shoulder whereby said collar may be transferred from the lower to the upper ends 40 of said blades and thereby lock said blades against engagement with the downwardly-facing shoulder to permit withdrawal of the choke.

13. In oil well apparatus of the type described, the combination of a tubing nipple having upwardly and downwardly-facing shoulders, of a choke insertable in said tubing nipple and having a plurality of locking blades, means acting intermediate the 45 ends of the blades for urging the blades out-

wardly, a collar to embrace said blades at either end thereof whereby to confine the embraced ends and prevent their engagement with obstructions, and yieldable means normally maintaining said collar in a position upon the choke where it embraces the lower ends of the blades.

14. In oil well apparatus of the type described, the combination of a tubing nipple having upwardly and downwardly-facing shoulders, of a choke insertable in said tubing nipple and having a plurality of locking blades, means acting intermediate the ends of the blades for urging the blades outwardly, a collar to embrace said blades at either end thereof whereby to confine the embraced ends and prevent their engagement with obstructions, yieldable means normally maintaining said collar in a position upon the choke where it embraces the lower ends of the blades, and means upon the blades engaging the collar to prevent downward movement of the collar upon the blades when the collar is positioned to embrace the upper ends of the blades.

15. In apparatus for controlling flow through the tubing of oil wells, a choke in said tubing and having an apertured oil admission bean, the aperture of which is formed at one end with a valve seat, a vertically movable valve to co-act with said seat, a weight in said tubing above said choke, means at the upper end of the tubing for supporting and vertically moving the weight, vertical movement of the weight seating and unseating the valve, and means to admit gas to the choke comprising an orifice in said choke above said bean.

16. In apparatus for controlling flow through the tubing of oil wells, a choke in said tubing and having an apertured oil admission bean, the aperture of which is formed at one end with a valve seat, a vertically movable valve to co-act with said seat, a weight in said tubing above said choke, means at the upper end of the tubing for supporting and vertically moving the weight, vertical movement of the weight seating and unseating the valve, and means to admit gas to the choke comprising an orifice in said choke above said bean, the choke having sealing means engaging the tubing above and below said orifice.

HERBERT C. OTIS.
